UNITED STATES PATENT OFFICE.

CHARLES B. BUERGER, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

METHOD OF OPERATING STILLS AND REMOVING COKE THEREFROM.

1,302,761.

Specification of Letters Patent.

Patented May 6, 1919.

Application filed February 7, 1918. Serial No. 215,764.

To all whom it may concern:

Be it known that I, CHARLES B. BUERGER, a citizen of the United States, residing in the city of Philadelphia, county of Philadelphia, and State of Pennsylvania, have invented certain new and useful Improvements in Methods of Operating Stills and Removing Coke Therefrom, of which the following is a specification.

10 My invention relates to a method of operating stills and removing coke or deposit from stills employed in oil refineries for reducing or distilling petroleum or petroleum distillate or residuum.

15 It is the object of my invention to provide a method which will make it possible promptly after completion of a still run, and without the loss of time incident to the cooling of the still and contents to a temperature making it possible for still cleaners to enter the still as in the old and common practice, to remove the coke or practically solid deposit from the still with greater economy in time and labor, whereby the period during which the still is not in operation in treating or distilling oil is materially reduced, and, consequently, the proportion of the time in which the still is in operation upon oil is materially increased.

20 To these ends I have provided a method of the character hereinafter described, in which there are employed within the still a plurality of frames, cages or pans within, around and above which the coke or the like is deposited and which are withdrawn, preferably in succession, in a horizontal direction from the still, suitably constructed for the purpose, each frame, cage or pan removing the contained and adjacent coke.

25 For an understanding of a mode of practising my method and an illustration of one of the forms my apparatus may take, reference is to be had to the accompanying drawings, in which:

30 Figure 1 is a side elevational view, partly in section, of a still constructed and equipped in accordance with my improvements.

Fig. 2 is a horizontal sectional view, partly in plan, of the structure illustrated in Fig. 1.

35 Fig. 3 is an end elevational view of the structure of Fig. 1.

Fig. 4 is a plan view of a cage or frame.

Fig. 5 is a side elevational view of the cage or frame of Fig. 4.

Referring to the drawings, S represents an oil still, here shown of the horizontal cylindrical type, suitably housed and supported by brickwork 1 forming beneath the still a firebox or combustion chamber F in which is developed the heat transmitted to the still contents through the still bottom B for distillation purposes in well known manner.

40 A pipe 2 serves to carry off oil vapors produced during the distillation process. The still may be provided if desired with the usual manholes 3, 3 at its top and the manhole 4 at one end. At one end of the still its bottom is a manhole 5 formed by a manhole member 6 whose lower side is of circular form conforming to the shape of the still bottom and whose upper side is illustrated as horizontal, Fig. 3, thereby forming a manhole of relatively great width and of a height preferably above the level of the coke deposited in the still. The member 6 has the front flanges 7 to which is bolted the flange 9 of the manhole cover 8.

45 In Figs. 4 and 5 is illustrated a cage or frame 10, rectangular in form, comprising the side members 11, 11 and the diagonal member 12, all secured at opposite corners of the frame by rivets 13. And extending through the parts of the members 11 and 12 which are so held by the rivets are the holes 14, 14 for attachment of chains 15 or the like.

50 The frame illustrated is one of many forms, it being understood that any other suitable shape or form is comprehended by my invention. For example, the frames may be triangular, hexagonal or any other suitable shape which will allow their placement close to each other within the still.

55 The frame illustrated has no bottom, and this is my preferred construction, though it will be understood that my invention is not limited to bottomless frames or cages, and that pans may be employed, which latter are comprehended within the terms frame and cage.

60 As shown in Figs. 1, 2 and 3, these frames are laid upon the bottom B of the still on the inside thereof in suitable numbers practically to completely cover the still bottom. The number of frames and their size is preferably such as to allow them to lie

close to the still bottom notwithstanding the buckling of the same which occurs in practice in this type of still due to the fact that the still bottom is operated at red heat.

5 The corners of the successive frames in the series are connected by chains 15 attached thereto at the holes 14 above referred to.

In the example illustrated, there are three frames per transverse row, the chain connections from one row to the next alternating on opposite sides of the still, the frames or cages being preferably so positioned that as they are successively pulled toward the left, Figs. 1 and 2, there is imparted to each 10 in succession a twisting or turning movement.

The operation is as follows:

When the cages or frames have been suitably placed within the still, the manhole 6 is closed by bolting on the cover 8. The

20 other still openings, as manholes 3 and 4, having been closed, oil to be treated is introduced into the still and operated upon in well known manner by application of heat produced in the fire chamber F.

25 During the process coke is deposited on the bottom of the still, and in it the frames 10 become embedded. As the still run approaches completion, the deposit becomes denser and denser and the final step is ordi-

narily to run to dryness, whereby coke or practically solid carbonaceous material lies to great depth on the still bottom. For this purpose the presence of the metallic frames 10 is of advantage in that the numerous 30 metal plates or strips of the frames readily conduct heat into the mass of coke or tar and assist in driving out all remanent oil.

When the still has been so run to dryness the run has been completed.

40 Thereupon, when necessary, steam is introduced into the still and allowed to flow for a time sufficient to displace the residual vapors and combustible atmosphere.

45 Immediately the manhole cover 8 is loosened it may be hoisted to the position indicated in Figs. 1 and 3 by any suitable hoisting apparatus 16 supported upon the bracket 17 carried by the still or otherwise suitably supported.

50 The chain 18, Fig. 2, is connected to the first frame 10 of the series, and connects to any suitable mechanism for exerting a pull upon the chain 18. For this purpose an ordinary power driven windlass or the like 55 may be employed. In so pulling upon the chain 18 the first frame 10 is given more or less of a twisting or turning movement, thereby loosening the coke adhering thereto or disposed within the same and the neighbor-

60 boring parts of the coke are separated from the remainder of the mass and from the still bottom. This first frame is pulled out through the manhole 5 and in so moving transmits a pull through the chain 15 connecting to the second frame, which removes

its mass of coke; then the chain 15 connected to the first frame of the second row is brought under tension, rotating or twisting the first frame of the second row and pulling it outwardly, and so on throughout the 70 series, the frames of a row being successively pulled and more or less rotated and then the next rows in succession.

By this action substantially all the coke within the still, practically 85% thereof as 75 has been found in practice, is removed a part at a time.

The coke when removed immediately after the completion of the run as described may be at red heat and upon contact with the 80 air may burst into flame. In such case the flaming coke as it comes from the still is quenched, as by playing a hose thereon.

By the above described mode or operation a great amount of heat existing within the 85 still at the end of a run is removed by actually removing the hot coke itself; and it is the red heat of the coke which under the old and common practice necessitated the cooling of the still, requiring approximately 90 six hours, before men could enter to break up the coke and remove it. When the hot coke has been removed in a relatively short time, say three quarters of an hour, as above described, after removal of the manhole 95 cover 8, the still may be entered and the small remaining amount of coke swept out through the manhole 5, the coke coming freely away from the metal shell of the still. The manhole 5 is of such form that there is 100 no ledge higher than the bottom B over which the frames and coke must be raised or drawn.

The frames, from which all coke has been removed outside the still, are then replaced 105 in the still, the manhole cover 8 replaced and the still recharged for the next run.

By the above described method and apparatus a still of a given size may be cleaned and recharged for the next run in about 110 three to six hours from the time the fire is drawn at the end of the preceding run, whereas with a still of like size and character under the old and common practice the time elapsing has been about twelve hours. 115

When under the old practice the still is run about sixty hours and is idle about twelve hours, by the method herein described a run of sixty hours is followed by an idle period of approximately only three to six 120 hours, whereby the total time of a run comprising distillation and idle periods is reduced from about 72 hours to about 65 hours. This means that with a given still equipment far more oil can be treated in a given time, 125 with the result that the investment in still structure is far more productive.

What I claim is:

1. The method of removing from a still the deposit formed therein in running the 130

still to dryness in treatment of oil, which consists in placing within the still a plurality of members which become embedded in the deposit as formed, and removing the deposit in sections by removing said members horizontally in succession from the still.

2. The method of removing from a still the deposit formed therein in running the still to dryness in treatment of oil, which consists in placing within the still a series of members movable independently of each other and connected in series and which become embedded in the deposit as formed, and removing the deposit by pulling and rotating said members in succession and withdrawing them from the still.

3. The method of removing from a still the deposit formed therein in running the still to dryness in treatment of oil, which consists in placing within the still a plurality of members movable independently of each other and connected in series in successive rows and which become embedded in the deposit as formed, and removing said deposit by removing said members in succession by exerting thereon a rotating force and a pull communicated in succession from one member to the next in the series.

4. The method of operating a coking still, which consists in placing in the still a series of members movable independently of each other and connected in series, distilling oil and running the residuum to dryness whereby said members are embedded in coke, immediately upon completion of the run and displacement of combustible vapors removing the hot coke in successive sections by pulling said members in succession horizontally from the still.

5. The method of removing from a still

having a substantially horizontally disposed bottom the deposit formed therein in running the still to dryness in treatment of oil, which consists in placing within the still a plurality of flexibly interconnected frames which become embedded in the deposit as formed, and removing the deposit in successive sections by removing said members horizontally in succession along the still bottom and through the head thereof.

6. The method of removing from a still having a substantially horizontally disposed bottom the deposit formed therein in running the still to dryness in treatment of oil, which consists in placing within the still a plurality of flexibly connected frames disposed in successive rows transversely of the still bottom and becoming embedded in the deposit as formed, and removing the deposit in sections substantially horizontally along the still bottom and through the still head by pulling and rotating said frames in succession and withdrawing them from the still.

7. The method of operating a coking still, which consists in placing upon the still bottom a series of flexibly connected members, distilling oil and running the residuum to dryness whereby said members are embedded in coke, immediately upon completion of the run and while the coke is still at a temperature at which it will kindle in contact with the air, pulling said coke in sections substantially horizontally along the still bottom through the still head into the atmosphere by removing said members in succession.

In testimony whereof I have hereunto affixed my signature this 4th day of February, 1918.

CHARLES B. BUERGER.
